UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

METHOD OF POINTING AND THREADING SCREWS, BOLTS, AND SIMILAR ARTICLES.

1,249,874.

Specification of Letters Patent. Patented Dec. 11, 1917.

Original application filed August 23, 1915, Serial No. 46,940. Divided and this application filed July 21, 1916. Serial No. 110,517.

To all whom it may concern:

Be it known that I, RICHARD LESTER WILCOX, a citizen of the United States, residing at Waterbury, in the county of New Haven and State of Connecticut, have invented a certain new and Improved Method for Pointing and Threading Screws, Bolts, and Similar Articles, of which the following is a specification, reference being had therein to the accompanying drawings.

My invention relates to a new and improved method for pointing and threading screws, bolts and similar articles, preferably with dies.

To these, and other ends, my invention consists in the method for pointing and threading screws, bolts and similar articles, substantially as hereinafter described and illustrated in the accompanying drawing, where-
20 in,—

Figure 1 is a plan view of a pair of thread rolling dies which may be used in my improved process;

Fig. 2 is a perspective view of one of such dies;

Fig. 3 is a face view thereof with the depth gage removed;

Fig. 4 is an end view thereof;

Fig. 5 is a face view of the depth gage;

30 Fig. 6 is an edge view thereof;

Figs. 7, 8, 9, 10 and 11 are enlarged sectional views of the die and depth gage, taken respectively upon lines A, B, C, D and E of figure 3, with the blank shown in connection therewith; and

Fig. 12 is a fragmentary plan view of one of the dies and depth gage with the blank in contact therewith.

Heretofore gimlet point screws have generally been produced by first pointing the blank in a shaving machine, lathe or similar mechanism and afterward forming the thread thereon or by rolling a V groove in the shank of a blank having a head at both ends thereof, and then threading the walls of said V groove, which thereby become the pointed ends of two bolts or screws, after which that portion of the shank between the V groove and the heads are threaded, but in my improved method the blanks having a head at only one end are pointed and threaded at one and the same

time and without the loss of any material, as is necessary under the old practice.

One form of means for practising my improved process is shown in the drawings, wherein the numeral 2 designates the fixed die and 1 the movable die, both being of substantially the same shape, differing only in their length, the movable die being longer than the fixed die and provided with a guide notch 3.

These dies are secured in the usual way in any one of the common forms of thread rolling machine. Each die has an angle recess 4 in one side thereof at an angle to the top and bottom and upon the adjacent faces are the ribs 5, which are parallel to the side of the dies and terminate at their inner ends at the edge of the recess 4.

The front face of each of the dies is provided with the usual thread rolling grooves 6, which extend from the outer edges of the die to and upon one side of the ribs 5 (see Fig. 2).

Secured within the recess 4, by a screw 7, is the depth gage 8, having the lip 9 upon one end thereof. The depth gage 8 is so shaped and designed that its position within the recess 4 may be reversed end for end if desired, and which is necessary if the dies are reversed so that the lower side becomes the top side and vice versa.

The contact face 11 of the lip 9 is slightly curved to allow for the elongation of the blank as the end thereof passes over it.

The dies 1 and 2 are so arranged that the ribs 5 upon one die move in the same plane as the ribs 5 upon the opposite die and the edges thereof have substantial contact with each other during this movement.

In practice, the blank, headed at only one end, designated herein by the numeral 10, is placed between the dies in the usual manner, with the bottom end thereof resting upon the contact face 11 of the lip 9, its alinement being determined by the guide notch 3, and its then position being substantially shown in Fig. 12. The guide notch 3 is not essential to the operation of the device but is common in thread rolling dies.

As the movable die 1 advances parallel with the face of the fixed die 2, the thread is rolled upon the shank of the blank from

the head down to a point near the bottom thereof, there being grooves 6 at this point to form the threads (see Figs. 7 and 8). As the threads are rolled, the blank is slightly elongated by stretching toward its bottom end, the engagement of the rolled threads and grooves 6 preventing elongation in the opposite direction, until the threads are substantially completed and the blank is at that 5 part of the die substantially designated by the line C in Fig. 3 and as illustrated in Fig. 9. At about this time the lower end of the blank is brought into contact with the ribs 5 and the elongated portion thereof is 10 tapered by reason of its contact therewith and is pointed substantially as shown in Fig. 11. During this pointing operation the grooves in the side of the ribs 5 roll the thread on the screw until the completed 15 blank is formed at that portion of the die substantially illustrated by line E in Fig. 3, and in Fig. 11.

The blank is only supported by the lip 9 of the depth gage 8 until such time as the 20 threads on the shank are of sufficient depth to insure the proper alinement of the blank in the die, and after this has been accomplished, the blank passes beyond the lip 9, as shown in Fig. 9, and there is nothing to 25 retard the elongating action of the blank through the thread rolling operation. This elongation of the blank continues while the thread is being rolled on the pointed portion, thus facilitating the pointing operation.

If the metal in the blank is of such a 30 nature that it will not flow by reason of the thread rolling operation, the blank is placed between the dies for substantially its full length, instead of slightly shorter, as is the 35 case with the blank composed of metal capable of flowing freely.

It will be observed that in the embodiment 40 of my invention, as herein described, gimlet pointed screws or bolts are pointed and threaded without waste of material, and the old pointing operation wherein material is wasted is eliminated.

In minor details the means adopted to 45 accomplish my new and improved method 50 may be altered and I do not therefore limit

myself to details thereof constructed exactly as shown and described, except as the scope of the claims requires.

Having described my invention, what I claim as new and desire to secure by Letters Patent, is:

1. A method of manufacturing articles as described, consisting in first rolling a thread on a portion of a blank and then progressively advancing the thread toward one end of the blank, elongating the blank toward the same end and tapering the elongated portion. 60

2. A method of manufacturing articles as described, consisting in first rolling a thread on a portion of a blank and then progressively advancing the thread toward one end of the blank, elongating the blank toward the same end, tapering the elongated portion and finally forming a thread 70 on the tapered elongated portion. 65

3. In a method of manufacturing articles as described, the use of dies which operate first to roll a thread on a portion of a blank and then progressively advance the thread 75 toward one end of the blank, elongating the blank toward the same end, tapering the elongated portion and finally forming a thread on the tapered elongated portion. 75

4. In a method of manufacturing articles as described, the use of dies provided with a depth gage for a blank and operating to first roll a thread on a portion of the blank and then progressively advancing the thread 80 to the end of the blank. 80

5. In a method of manufacturing articles as described, the use of dies provided with an adjustable depth gage for a blank and operating to first roll a thread on a portion 85 of the blank and then progressively advancing the thread to the end of the blank. 90

6. The process of pointing a blank and rolling a thread thereon without waste of material, which consists in rolling a thread upon a portion of the shank, which is elongated thereby, and then pointing and rolling a thread upon said elongated portion. 95

In testimony whereof I have hereunto affixed my signature.

RICHARD LESTER WILCOX.
